UNITED STATES PATENT OFFICE.

WILLIAM S. STOCK, OF PORTLAND, OREGON.

DESIGN FOR A CONTAINER FOR SACHET-POWDER OR SIMILAR ARTICLES.

59,438.

Specification for Design.

Patented Oct. 18, 1921.

Application filed December 23, 1920. Serial No. 432,878. Term of patent 7 years.

To all whom it may concern:

Be it known that I, WILLIAM S. STOCK, a citizen of the United States, residing at Portland, in the county of Multnomah and State of Oregon, have invented a new, original, and ornamental Design for Containers for Sachet-Powder or Similar Articles, of which the following is a specification, refer-

ence being had to the accompanying drawing, forming part thereof.

The drawing shows a side elevation of a container showing my new design.

I claim:

The ornamental design for a container for sachet powder or similar article, as shown.

WILLIAM S. STOCK.
